UNITED STATES PATENT OFFICE.

CATHERINE SWAIN, OF NEW YORK, N. Y., ASSIGNOR TO THE BUTTERICK PUBLISHING COMPANY, (LIMITED,) OF SAME PLACE.

DESIGN FOR A LADY'S WALKING-SKIRT.

SPECIFICATION forming part of Design No. 18,484, dated July 24, 1888.

Application filed June 15, 1888. Serial No. 277,270. Term of patent 3½ years.

To all whom it may concern:

Be it known that I, CATHERINE SWAIN, of the city, county, and State of New York, have invented and produced a new and original Design for a Pattern of a Lady's Walking-Skirt; and I do hereby declare that the engraved prints accompanying this specification convey to any one accustomed to using paper patterns a clear understanding of how a garment made up by the pattern will appear.

The design shows a round four-gored skirt that displays a full drapery hanging in oval outline quite near the edge at the center of the back and some distance from the edge at the center of the front, and revealing the skirt

nearly half-way up at the sides, where the edges fall in jabots, the drapery exhibiting groups of plaits turning in opposite directions on each side of a box-plait falling over each hip, and flaring and jabot folds at the back.

2c

What I claim as my invention, and desire to secure by Letters Patent, is—

The design for a lady's walking-skirt, as shown in the engraved prints accompanying this specification.

CATHERINE SWAIN.
